DOOR ELEVATING DEVICE

Carl Lute, Hammond, Ind., assignor to Camel Company, Chicago, Ill., a corporation of Illinois

Application March 14, 1931, Serial No. 522,608

10 Claims. (Cl. 16—99)

This invention relates to doors for railway house cars and concerns itself primarily with devices adapted to elevate such doors above the supporting surface whereby sliding movement may be imparted to them.

It is an object of this invention to provide a simple, inexpensive and easily operable structure to effect elevation of sliding doors.

A further object is the provision of elevating devices, including operating bars, which may be rapidly assembled with the door, the devices permitting assembly and replacement of said bars without removing the doors from the car.

Another object of the invention is the provision of an elevating construction designed so that the moving parts thereof may be replaced without the necessity of removing the door from the car.

This invention also has for an object the provision of lift devices for a sliding door by means of which the door is biased toward closing position during the lowering movement of the door.

Other objects and advantages of lifting devices of this invention will become apparent from a consideration of the description thereof and the drawings forming part of the specification.

In the drawings:

Figure 1 is a partial elevation of a car door to which the preferred embodiment of the invention is applied.

Figure 2 is a section taken on line 2—2 of Figure 1.

Figure 3 is a sectional view taken on line 3—3 of Figure 1.

Figure 4 is a sectional view taken on line 4—4 of Figure 1.

Figure 5 is a sectional view taken on line 5—5 of Figure 1.

Figure 6 is a fragmentary elevation showing a modified lift mechanism.

Figure 7 is a sectional view taken on line 7—7 of Figure 6.

Figure 8 is a sectional view taken on line 8—8 of Figure 6.

Figure 9 is a detail of a roller housing.

Figure 10 is a sectional view taken on line 10—10 of Figure 9.

Figure 11 is a partial elevation showing a further modification of the lift mechanism, the door being illustrated in lowered position.

Figure 12 is a view similar to Figure 11, the door being shown in elevated position.

Figure 13 is a sectional view taken on line 13—13 of Figure 11.

Figure 14 is a horizontal section taken on line 14—14 of Figure 11.

Figure 15 is an enlarged elevation of the lower right hand corner of the door, illustrating another modification of the invention.

Figure 16 is a sectional view taken on line 16—16 of Figure 15.

In the consideration of the doors to which the various forms of the invention are applied it may be considered that the doors shown in Figures 1 and 6 are box car doors or the main door

of the double doors customarily employed on automobile cars. In either view of this consideration it is observed that these doors in their closing movement move toward the left as viewed in Figures 1 and 6.

The doors illustrated in Figures 11 and 14 may be considered as box car doors or as the auxiliary door of a double door construction usually employed on automobile cars. These doors in their closing movement move toward the right as viewed in Figures 11 and 14.

The reason for this consideration of the doors will become apparent hereinafter.

Referring now to the embodiment of the invention illustrated in Figures 1 to 5, inclusive, there is shown a metallic door 10 provided with a plurality of horizontal corrugations 11—11 and

marginal vertical corrugations 12—12. The door shown in these figures is for the purpose of illustration only and the invention applied to the door is not limited to the particular construction noted above but may be employed as readily with doors of any type.

Secured to the lower marginal portion of the door is an angle bar 13 which, in the normal or lowered position of the door, is adapted to have frictional engagement with a track 14 secured to the side sill (not shown) of the car by means of a plurality of brackets 15, one of which is illustrated in part

in Figure 2 of the drawings. The track member of the present embodiment takes the form of an angle bar having one of its legs 16 positioned in a horizontal plane and by which it is secured to the bracket members 15 by means of rivets 17.

This horizontal leg constitutes as well the tread of the track. The other leg 18 of the track depends from the horizontal leg 16 and serves as a reinforcing means and, additionally, for a purpose hereinafter set forth.

In order to move the door toward open or closed position it is essential that the door be elevated, thereby being released from its frictional engagement with the track. For the accomplishment of this result there is disclosed a plurality of hangers indicated generally by the reference numeral 19, one of which is secured adjacent each of the lower corners of the door.

5

These hangers are preferably identical in construction, thereby avoiding the construction of right and left hangers.

Each hanger 19 comprises a body portion 20 which is fastened to the door by means of a plurality of rivets 21-21 extending through attaching flanges 22 formed on said body portion. The body portion is also provided with a horizontal flange 23 and spaced vertical flanges 24-24, 10 these flanges extending substantially at right angles to the door. Extending outwardly from each of said vertically extending flanges is a lobe 25 and extending inwardly from each of said flanges adjacent the upper portions thereof is a projection 26. A cover member 27 is provided with outwardly extending lobes 28 coextensive with the lobes 25 formed on the vertical flanges 24-24 of the body member. The cover member is adapted to be secured preferably by riveting to 20 the body member the rivets extending through aligned openings in the pairs of lobes provided on said members and through aligned openings provided in said cover member and in the projections 26 formed on the flanges 24-24. Each of 25 the vertical flanges 24 of the body member is provided with a substantially angular slot 29, the contour of which is completed by means of the cover member. These slots in the hanger or bracket members 19 are aligned for a purpose 30 hereinafter indicated. The body member 20 is provided with an opening 30 while the cover member 27 is provided with a bearing 31 positioned oppositely from said opening formed in the body member. The cover member extends 35 downwardly below the track 14 and is provided with an upwardly extending flange 32 adapted for engagement with the depending leg 18 of the track in order to prevent disengagement of the lower portion of the door from the track.

40 It will be noted that the association of the body member 20 and the cover member 27 provides a compartment in which a roller 33 is adapted to be positioned. The roller 33 is mounted in a housing member 34 and is positioned in engagement with the track 14. To permit such engagement the reinforcing angle bar 13 is coped out as indicated at 35. The housing member 34 is clearly illustrated in greater detail in Figures 9 and 10 of the drawings. It constitutes side members 36-36 connected together by means of a wall W. These side members 36-36 are open along their lower margins in order to permit the roller 33 to extend therethrough. One of the side walls is provided with an opening 37 while in 55 the other side wall an embossment 38 is formed in alignment with the opening 37. The embossment, together with the opening constitute aligned bearings adapted to receive a pin 39 upon which the roller 33 is rotatably mounted. Extending outwardly from the side walls 36 in eccentric relation therewith is a plurality of trunnions 40-40 and extending upwardly from said housing member is a projection 41. In the assembly of said roller housing and its roller with 60 the body and cover members of the hangers or brackets the trunnions 40-40 are journaled in the bearings 30-31 provided in the body member 20 and in the cover member 27 respectively. It will be apparent from this assembly that the housing member 34 is pivoted eccentrically in the 65 brackets.

70 An operating bar 42 is employed to effect movement of said roller housings. This operating bar is adapted to extend through the aligned slots 29 formed in the hanger or bracket members. The

operating bar 42 in the present embodiment of the invention takes the form of an angle member. The horizontal leg of this member is coped out as indicated at 43 adjacent each end thereof and through these coped portions the projections 41 of the housing members 34 are adapted to extend. Secured to the operating bar is an abutment member 44. Mounted on the door adjacent to said abutment member is a bracket 45, this bracket being extended in embracing relationship with the vertical leg of the operating bar 42 as indicated at 46 in Figure 3 of the drawings, thereby preventing displacement of said bar outwardly away from the door. Adjacent the upper portion of said bracket member 45 a boss 47 is provided for pivotally mounting an operating lever 48. This lever 48 is formed at its lower end with a nose portion 49 adapted to have engagement with the abutment member 44 fastened on the operating bar. The operating lever 48 extends upwardly above the boss 47 and lies in an inclined position. A strap 50, preferably of arcuate form, is secured to the door as clearly shown in Figures 1 and 4 of the drawings. The operating lever 48 is provided with a downwardly extending finger 51 spaced from the rear side of said lever and engaging behind the strap member 50. A hand grip portion 52 is provided at the upper end of said lever. The strap member 50 is provided with stops 53 and 54 for limiting the movement of the lever.

A modification of the invention is illustrated in Figures 6, 7 and 8 of the drawings. In this modification the body portion 60 of the bracket or hanger members is rigidly secured to the door and a separate cap member 61 covering the upper portion of said body member is also fastened to the door. The body member in this modification is provided with a depending portion 62 provided with an upwardly extending flange F adapted to have engagement with the vertically extending leg 18 of the track member 14. The roller housing member 34 is adapted to be journaled in bearings 63 and 64 provided in said body member 60. It will be noted that the cap member is of much smaller extent than the cover member illustrated in Figures 1 to 5, inclusive, of the drawings and that the body member and cap member when assembled on the door provide, together, an angular slot 65 through which the operating bar 42 is adapted to extend. As in the previous embodiment considered the housing member 34 is provided with an upwardly extending projection 41 adapted to extend through a corresponding coped portion 43 formed in the operating bar. It will be noted that in each of the embodiments considered the cover member or the cap member may be removed from the door without the necessity of disturbing the position of the body member. In order to avoid interference between the operating bar 42 and the vertical corrugations 12 during the movement of said bar it has been found advisable to chamfer a portion of the horizontal leg at each end of the bar as indicated at 66 in Figure 8 of the drawings.

Referring now to the modification of the invention shown in Figures 11 to 14, inclusive, there is disclosed a bracket or hanger construction embodying a backing plate 70 and a cover portion 71, these parts being riveted to the door as clearly indicated in Figure 14 of the drawings. An operating bar 72 in the form of a channel member extends through aligned slots 73 in the cover portions 71. The lower horizontal flange of the channel operating bar 72 is coped out adjacent 75

each end and extending through said coped portions are the projections 74 of the housing members 75. The upper horizontal flange of the bar 72 is coped out as indicated at 76 and the nose 77 of an operating lever 78 is adapted to be positioned within said coped out portion. This operating lever 78 is pivotally mounted on the door by means of a boss 79 formed on a bracket member 80 secured to said door. A strap member 81 is adapted to embrace said lever and offset portions 82 and 83 formed on said strap member serve as stops or abutment members to limit the movement of said operating lever. It will be observed that in this embodiment the projection 74 formed on the housing member 75 is positioned in substantial alignment with the outer face of said housing member. In this construction engagement between the track 84 and the upwardly extending flange 85 on the body portion 71 is effected. As clearly indicated in Figure 14 it is noted that the housing member is pivotally supported by means of the trunnions 86 and 87 in bearing members 88 and 89 formed, respectively, in the backing plate and in the body portion.

It may be found desirable in certain instances to effect greater surface engagement between the hangers or brackets and the track in order to prevent the door from becoming disengaged from the track. The embodiment illustrated in Figures 15 and 16 of the drawings provides a construction whereby this may be obtained. It is noted that the bracket or hanger 90 is provided with a downwardly extending portion carrying an upwardly extending flange 91 having engagement with the depending flange 92 of the track 93. In addition to this engagement the housing member 94 is also provided with an upwardly extending flange 95 having engagement with the depending flange 92 of the track. By this construction it will be apparent that substantial engagement between the upturned flange 95 formed on the housing member 94 will always be maintained inasmuch as said housing member has only limited pivotal movement relative to the track.

It is believed that the operation of the embodiments of the invention hereinbefore described will be readily apparent. In each of the embodiments it will be clear that a downward pull upon the operating lever will result in horizontal movement of the operating bar. This movement of the bar, because of the engagement between the upwardly extending projections formed on the roller housing members and the bar, will in turn be imparted to said roller housing members. Inasmuch as the roller housing members are journaled in the hanger or bracket members the housings will tend to rotate relative thereto. However, since the housing members are journaled or pivoted in said hanger or bracket members in eccentric relation thereto, and inasmuch as the rollers mounted in said housing members are in engagement with the tracks, said housing members will be fulcrumed upon the rollers and rotation of said members upon said rollers will effect an elevating movement of said housing members where they are journaled in the hanger or bracket members. This elevating movement manifestly will be imparted to the hanger members and since these are secured to the door, the door will be elevated.

It is further apparent from the construction in Figures 1 to 5, inclusive, that removal and replacement of all of the moving parts of the hanger construction may be readily effected with-

out the necessity of removing the car from its track. It is apparent that by removal of the rivets which secure the cover member to the body member the operating bar as well as the roller housing with its roller become readily available and may be easily removed. In the embodiment of the invention shown in Figures 6 to 8, inclusive, the removal of the cap member 61 will at once expose the operating bar 42 so that it may be removed if necessary. This clearly may be accomplished without disturbing the remainder of the hanger construction and without removal of the door from the car. In the construction shown in Figures 11 to 14, inclusive, removal of the operating bar may be effected without removal of the door from the car by simply jacking up the door relative to the track. As the door is thus elevated the operating bar may be moved horizontally until it is disengaged from the upwardly extending projections, whereby said bar may be slid out from the hangers through the slots provided therein. In the construction shown in Figures 15 and 16 it is evident that greater gripping engagement between the hangers or bracket members and the track is effected. It is apparent from a consideration of the movement of the roller housing members in the elevating operation of the door that said members have merely pivotal movement upon the pins which secure the rollers rotatably in said housings and not an elevating movement relative to the track. Consequently, it is clear that gripping engagement between said housing members and the track in the lowered position of the door will provide greatly increased security against all possible displacement of the door from the track.

Attention is invited to the fact that in the door shown in Figure 1 of the drawings, which represents a box car door or the main door of a double door construction for an automobile car, and which in its closing movement travels toward the left as viewed in Figure 1 the connection between the roller housing members and the bracket or hanger members is positioned to the left of the pins upon which the rollers are mounted. Similarly the door shown in Figures 11 and 12 of the drawings, which may be considered a box car door or an auxiliary door of a double door construction for automobile cars and which as viewed in these figures moves toward the right toward closed position, the connection between the roller housings and the hanger or bracket members is positioned to the right of the pins upon which the rollers are mounted. In view of the relationship noted above there is effected during the lowering movement of the door a movement of translation of the door toward its closed position. This effect is very desirable inasmuch as because of the action indicated above it is possible to eliminate closing mechanism for bringing the door to fully closed position.

It is manifest that numerous modifications and changes in the details of the embodiments of the invention disclosed may be made without departing from the spirit of said invention. It is intended that all such changes and modifications are comprehended within the invention, which is to be limited only by the scope of the claims appended hereto.

I claim:

1. In combination, a sliding door, a track, means establishing frictional engagement between said door and said track to prevent sliding movement of said door in its lowered position, a plurality of brackets secured to said door, aligned bearings

- formed on each of said brackets, a roller housing provided with eccentric trunnions positioned in each of said brackets with said trunnions journaled in said bearings, rollers carried by said housings, said rollers adapted to have rolling engagement with said track and means including a substantially horizontally movable unitary member for imparting movement in the same direction to said roller housings to elevate said door, said rollers serving as fulcrums during said elevating movement.
2. In combination, a sliding door, a track, said door in its lowered position frictionally engaging said track, a plurality of brackets secured to said door, a roller housing pivoted eccentrically in each of said brackets, a roller mounted in each of said housings in engagement with said track, a horizontally movable operating bar, an opening provided in said bar adjacent each of said roller housings, a lobe provided on each housing extending through a contiguous opening and means for moving said bar to elevate said door.
3. The combination with a sliding door provided with a vertical outwardly extending corrugation adjacent each margin of the door and a track with which said door is adapted to have frictional engagement in its normal position, of means for elevating said door, comprising brackets secured to said door, a roller housing pivoted eccentrically in each of said brackets, a roller mounted in each of said housings in rolling engagement with said track, a horizontally movable operating bar for imparting movement to said roller housings, said brackets being provided with aligned openings disposed forwardly of said vertical corrugations, whereby said bar may be assembled with said brackets and housings by sliding movement through said bracket openings after said brackets and housings have been assembled with the door.
4. In combination, a sliding door, a track positioned below said door provided with a depending flange, said door in its normal position adapted to have frictional support upon said track, a plurality of roller housings pivoted eccentrically on said door, each of said housings being provided with a depending portion having an upwardly extending flange adapted to coact with the depending flange of said track to prevent outward displacement of the lower portion of said door, a roller mounted in each of said housings and adapted to have rolling engagement with said track and means for imparting movement of rotation to said roller housings to elevate the door.
5. In combination, a sliding door, a track, said track having a depending flange, said door in its normal position adapted to have frictional engagement with the track, a plurality of brackets secured to said door, each of said brackets being provided with an upwardly extending flange, a roller housing pivoted eccentrically in each bracket, a roller mounted in each housing and adapted to have rolling engagement with said track, said roller housings having upwardly extending flanges, said flanges of the brackets and the housings being adapted to interengage with the depending flange of said track and means for imparting movement to said roller housings for the purpose set forth.
6. In combination, a sliding door, a track, said door in its lowered position being frictionally retained against sliding movement by said track, a pair of brackets secured to said door, roller housings pivoted eccentrically in said brackets, means for mounting a roller in each of said housings in engagement with said track, said roller mountings being horizontally offset from their respective housing pivots and means for imparting simultaneous movement of rotation in the same direction to said roller housings about said rollers as fulcrums, including a bar movable substantially horizontally in a single direction and engageable with said housings above the roller mounting means.
7. In a door elevating device for railway cars, in combination, a plurality of brackets, each of said brackets comprising a main body portion adapted to be rigidly secured to a car door, said body portion being open, and a cover portion for closing said opening, means for securing said body and cover portions together, roller mechanisms eccentrically journaled in said brackets and an operating bar having portions lying within said brackets and engaging said roller mechanisms, said securing means being positioned outwardly in spaced relation to said door whereby it is accessible for removing said cover plate while said door is mounted upon a railway car.
8. In a door elevating device for railway cars, in combination, a plurality of brackets, each of said brackets comprising a main body portion adapted to be rigidly secured to a car door, said body portions being partly open, roller mechanisms positioned in said brackets, an operating bar for said roller mechanisms having portions lying in the openings in said main body portions, cover plates for said body portions, means securing said cover plates in rigid relationship with said body portions for maintaining said bar in position, said means being removable and replaceable while said door is mounted upon a railway car.
9. In combination, a sliding door, a track, said door in its lower position having frictional engagement with said track, a plurality of roller housings pivotally mounted on said door, rollers, means for mounting a roller in each of said housings in offset relationship to said pivotal mounting and in engagement with said track, an operating bar carried by said door, said bar being movable substantially horizontal in a single direction to engage said roller housings for imparting rotation thereto about said rollers as fulcrums, whereby an elevating force will be exerted upon said door at the pivotal mountings between said housings and said door.
10. A hanger for car doors comprising a main body portion adapted to be rigidly secured to a car door, said body portion having outwardly extending flanges forming a pocket, roller mechanism positioned in said pocket in exposed position, a separate cover portion, and means securing said cover portion to said flanges of said main body portion for covering said roller mechanism, said means being disposed in spaced relation to said door, whereby said securing means and said cover portion may be removed while said door is mounted upon a car to expose said roller mechanism.
